POWER SUPPLY WORK CENTER FOR MAINTENANCE AND REPAIR OF ELECTRONIC EQUIPMENT

William J. Siegel, 814 E. Franklin Ave.,
Silver Spring, Md. 20901

Filed May 31, 1966, Ser. No. 2,480

Term of patent 14 years

(Cl. D26—15)

FIG. 1 is a front perspective view of a power supply work center for maintenance and repair of electronic equipment showing my new design;

FIG. 2 is a front view thereof; and

FIG. 3 is a side view thereof.

The back and base are substantially unadorned.

I claim:

The ornamental design for a power supply work center for maintenance and repair of electronic equipment, as shown and described.
